UNITED STATES PATENT OFFICE.

ALFRED J. HAYDEN, OF PUEBLO, COLORADO.

DESIGN FOR A SLIDE-FRAME FOR BUCKLES.

SPECIFICATION forming part of Design No. 24,399, dated June 18, 1895.

Application filed March 26, 1895. Serial No. 543,285. Term of patent 14 years.

To all whom it may concern:

Be it known that I, ALFRED J. HAYDEN, a citizen of the United States, residing at Pueblo, in the county of Pueblo and State of Colorado, have invented and produced a new and original Design for a Slide-Frame for Buckles, of which the following is a specification.

In the drawings, Figure 1 is a plan view of my design. Fig. 2 is a side view.

The leading feature of my design consists in a slide frame with projecting ears or wings.

The slide frame is rectangular with side bars having projecting ears or wings, with a

lateral cross bar connecting the side bars on one side and a longitudinally extending plate on the other side between the end bars of the slide frame.

I claim—

The design for a slide frame for buckles herein shown and described.

ALFRED J. HAYDEN.
